CLAIM

I claim the ornamental design for a video recorder for vehicle, as shown and described.

DESCRIPTION

FIG. 1 is a perspective view of a video recorder for vehicle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is a reference drawing that explains the state of use of the design;

FIG. 9 is a side view thereof;

FIG. 10 is a side view thereof, shown in an alternate position;

FIG. 11 is a side view thereof, shown in another alternate position;

FIG. 12 is a side view thereof; and,

FIG. 13 is a side view thereof, shown in another alternate position.

The broken lines contained in FIGS. 8-13 are for the purpose of illustrating the environmental structure and form no part of the claimed design.

1 Claim, 8 Drawing Sheets
